Primary Examiner — Paula Greene(74) Attorney, Agent, or Firm — Shook, Hardy & Bacon L.L.P.(57) CLAIM

The ornamental design for a removable toilet seat handle, as shown and described.

DESCRIPTION

FIG. 1 is a top perspective view of the handle of the present invention;

FIG. 2 is a top plan view thereof;

FIG. 3 is a right side elevation view thereof, the left side being a mirror image thereof;

FIG. 4 is a bottom plan view thereof;

FIG. 5 is rear side elevation view thereof; and,

FIG. 6 is a front side elevation view thereof.

The surface shading lines are provided only to indicate the character and/or any contour or curvature of the surfaces. They do not indicate color, texture, markings that actually exist thereon, indicia, graphic representations, surface treatment, or any other ornamentation applied to the article.

1 Claim, 2 Drawing SheetsFIG. 1.

FIG. 2.

FIG. 3.

FIG. 4.

FIG. 5.

FIG. 6.
